UNITED STATES PATENT OFFICE.

CARL VETTER, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

INDIRECT-DRIVE MECHANISM FOR WINDING MACHINES.

Application filed July 11, 1923. Serial No. 650,953.

To all whom it may concern:

Be it known that I, CARL VETTER, a citizen of the United States, residing at North Andover, in the county of Essex and State 5 of Massachusetts, have invented certain new and useful Improvements in Indirect-Drive Mechanism for Winding Machines, of which the following is a specification.

This invention has to do particularly with 10 the delivery devices of tape condensers and of apron condensers. It may, however, be used to advantage with any other textile machine in which a headed spool is driven by a drum, such as winding machines, spoolers and spinning mules whenever it is desirable to have a drum of less diameter than the spool heads.

In condensers of various types, it is considered desirable in the United States practice to use spools having relatively large 20 heads on which to wind the roving as it is taken from the card.

Such heads protect the barrel while it is being transported and help to hold the package 25 from slipping off the ends.

On a tape condenser where there are four or more drums, each driving a spool, it is desirable to reduce the size of the drum so that the operator can reach between the 30 drums from the back to care for the machine, as it is not convenient nor possible to reach in from the side.

A spool with a ten-inch head is in general use and it is usually necessary to drive it 35 with a ten-inch drum, but with my device a $6\frac{1}{4}$ in. drum can drive a spool with a ten-inch head. This allows four inches extra space between the four drums.

With my preferred construction, I use a 40 positive indirect drive in which all gears are protected and which can be adjusted for drums of different lengths.

In the drawings, Fig. 1 is a diagrammatic 45 back view of the delivery end of a condenser with my device.

Fig. 2 is an enlarged side sectional elevation looking from the right of line 2-2 on Fig. 1.

Fig. 3 is an enlarged side sectional elevation looking from the right of line 3-3 on Fig. 1.

Fig. 4 is a sectional elevation of my slide

bracket, head and drum viewed from the left of Fig. 3.

Fig. 5 is an elevation of the slide bracket 55 head from the opposite side to Fig. 3.

Fig. 6 is a view similar to Fig. 3 with part of the head broken away to show the interior.

Fig. 7 is a view similar to Fig. 3 of the 60 bracket at the other end of the drum from the outside.

Figs. 8 and 9 are fragmentary views similar to Fig. 6 showing other driving mechanism.

In the drawings, Fig. 1 is an elevation of the delivery end of a tape condenser of a common type having a frame indicated by N. As shown, there are four spool driving drums K, K, K, K, each of which is positively driven from any source of power as by means of a pulley P, and each of which drives frictionally a roving spool S. 70

In the construction shown, I provide for each set of spool and drum a supporting 75 girt O which is fixed at each end to the frame N in a convenient position.

As is usual in such machines, there are for each spool two spool arms M, M each adjustably supported by a girt rod O, each having 80 the usual extension 11 for an extra empty spool, not shown, and the spool supporting guides 10 and 12 which slope upwardly at about a right angle with each other. Arms M are each carried by and adjustable on a 85 girt rod O by means of set screws such as 41.

Each spool S comprises a barrel 51 upon which the roving is wound and which is in frictional contact with a drum K, two heads 90 52, 52, and bearing spindles 50 each of which rests on a guideway 10 in a well known manner.

Adjustably fixed to each girt O, preferably, by means of set screws such as 40, are 95 two drum arms B arranged to extend up and forward in the direction of spool arms M and each having a slide bracket guideway 45. The axes of these slide guideways coincide.

43 represents the traverse wires usual in such machines.

On the side of the machine where the drive pulleys P are located, I provide a slide

bracket A which includes a tubular sleeve 28 slideable axially and revoluble in a guideway 45. It can be adjusted therein and fixed in position by means of a set screw 46.

5 This slide bracket may be cut away at 27 to allow the head 52 of a spool to be slightly larger than would be otherwise possible, and has an axial bearing hole 26 for the drive shaft C on which is carried the drive 10 pulley P.

10 Each drum K is, preferably, constructed with interior spiders 35 whereby it is carried by a drum shaft 32 which is no longer than the drum.

15 One end of this drum shaft is carried by an arm 23 preferably integral with and forming part of slide bracket A which, preferably, carries a hub 22 in which is a bearing 21 therefor. 29 is an oil hole.

20 Its other end may be carried by another slide bracket T having a cylindrical shank 60 similar in all respects to sleeve 28 except that it need not be tubular as there is no need of a drive shaft on this end. This slide 25 bracket T has an arm 61 with, preferably, a hub 64 in which is a bearing 62 for the other end of drum shaft 32.

By means of the set screws 46 the position 30 of slide brackets A and T can be adjusted so as to conform to drums of different lengths and also to swing up or down to the correct adjusted position with reference to the barrel of the spool S.

On the inside of drum K, at the driving 35 side, I provide an internal gear 31 which is in mesh with a spur gear 30 carried by drive shaft C whereby the drum is positively driven.

To keep flyings from the gears and to 40 avoid the possibility of roving getting inside the drum, I prefer to provide each drum at each end with an internal annular groove 33 in which fits a head, such as H or 63, carried by and practically forming an 45 integral part of the slide bracket arm 23 or 61. The drum revolves around these heads, which are so positioned that the centre of each is the centre of the drum shaft bearings, but do not support the drums, that 50 function being performed by the drum shaft 32 and arms 23 and 61. The outside of each head H and each arm 23 and 61 should be flush with the end of the drum and inside the spool heads.

55 I might use for my drive a spur bevel gear such as 70 and internal bevel gear 71, as shown in Fig. 8, or a friction roller 73 in contact with the interior 74 of drum K as shown in Fig. 9.

60 It is apparent that the protecting heads H and T, instead of being integral with arms 23 and 61, might be fastened thereto in many ways or might be omitted entirely.

65 It is to be understood that my device may be used in a machine in which the ma-

terial on the spool is unwound as well as on one in which it is wound, and the expression "textile winding machine" in the claims is intended to include such an unwinding machine.

70 I claim:

1. The combination in a tape condenser having a frame; of a girt fixed therein; spool arms adjustably carried thereby; headed spools carried by said arms; drum 75 arms adjustably carried by the girt each having a slide bracket guideway; a slide bracket having a drum supporting arm, a head, a drum shaft bearing and a tubular sleeve slideable and revoluble in a guideway; a slide bracket having a drum supporting arm, a head, a drum shaft bearing and a shank slideable and revoluble in a guideway; means to adjust each slide bracket in its 80 guideway; a drum shaft carried in the drum shaft bearings; a headless drum of less diameter than the spool heads and as long as the drum shaft carried by the drum shaft of such size as to fit over said heads and having at one end an internal gear; a drive shaft revoluble in said sleeve; and a spur gear so carried by the shaft as to engage said internal gear.

2. The combination in a textile winding machine having a frame; of a spool revolvable therein; drum arms each having a slide bracket guideway carried by the frame; a slide bracket having a drum supporting arm, a head, a drum shaft bearing and a tubular sleeve slideable and revoluble in a 95 guideway; a slide bracket having a drum supporting arm, a head, a drum shaft bearing and a shank slideable and revoluble in a 100 guideway; means to adjust each slide bracket in its guideway; a drum shaft carried in the drum shaft bearings; a headless drum as long as the drum shaft carried by the drum shaft of such size as to fit over said heads and having at one end an internal gear; a drive shaft revoluble in said sleeve; and a 105 spur gear so carried by the shaft as to engage said internal gear.

3. The combination in a textile winding machine having a frame; of a spool having heads and revolvable therein; drum arms 115 carried by the frame each having a slide bracket guideway; a slide bracket having a drum supporting arm, a head, a drum shaft bearing and a tubular sleeve slideable and revoluble in a guideway; a slide bracket having a drum supporting arm, a head, a drum shaft bearing and a shank slideable and revoluble in a guideway; means to adjust each slide bracket in its guideway; a drum shaft carried in the drum shaft bearings; a headless drum as long as the drum shaft carried by the drum shaft of such size as to fit over said heads inside the spool heads and having at one end an internal gear; a drive shaft revoluble in said sleeve; and a spur 120 gear so carried by the shaft as to engage said internal gear.

125

gear so carried by the shaft as to engage said internal gear.

4. The combination in a textile winding machine having a frame; of a spool having heads and revoluble therein; drum arms carried by the frame each having a slide bracket guideway; a slide bracket having a drum supporting arm, a drum shaft bearing and a sleeve slidable in a guideway; a slide bracket having a drum supporting arm, a drum shaft bearing and a shank slidable in a guideway; means to adjust each slide bracket in its guideway; a drum shaft carried in the drum shaft bearings; a headless drum as long as the drum shaft carried by the drum shaft of such size as to fit inside the spool heads and having at one end an internal gear; a drive shaft revoluble in

said sleeve; and a spur gear so carried by the shaft as to engage said internal gear. 20

5. The combination in a textile winding machine; of a spool having heads and revoluble therein; a headless drum of less diameter than the spool heads and of less length than the distance between them carried by a drum shaft of less length than the distance between the spool heads; drum shaft brackets attached to the frame each having an arm which extends into the drum and has a bearing for the drum shaft; a drive shaft 30 which extends through one drum shaft bracket into the drum; and driving means between the drive shaft and the inside of the drum.

CARL VETTER.
